BUTTON HOLE MACHINE COMPANY, OF BOSTON, MASSACHUSETTS, A COR-
PORATION OF MAINE.

THREAD CUTTER AND CLAMP FOR BUTTONHOLE-SEWING MACHINES.

1,152,464.

Specification of Letters Patent.

Patented Sept. 7, 1915.

Application filed June 1, 1914. Serial No. 842,278.

To all whom it may concern:

Be it known that I, FRANK ZALESKI, a subject of the Emperor of Germany, residing at Somerville, county of Middlesex, 5 State of Massachusetts, have invented an Improvement in Thread Cutters and Clamps for Buttonhole-Sewing Machines, of which the following description, in connection with the accompanying drawing, is a specification, like characters on the drawing representing like parts.

This invention relates to buttonhole sewing machines of that type which comprise an upper thread mechanism and an under thread mechanism that coöperate to produce the edge stitches on a buttonhole, and the principal object of the invention is to provide novel means for cutting both the under and the upper threads upon completion of 20 the buttonhole. Means are also provided for clamping the severed end of the under thread so that when the stitching on a fresh buttonhole is started it will not be necessary for the operator to draw out a length of the 25 under thread and hold the latter while the first loops are being formed.

In order to illustrate my invention and give a proper understanding thereof I have shown it as it would be applied to a buttonhole sewing machine of the type commonly known to the trade as the "Reece" machine. Examples of the so-called "Reece" machine may be found in the following United States Letters Patent: No. 494,280, March 28, 1893; 30 No. 498,216, May 28, 1893; No. 655,637, August 7, 1900. As will be seen by reference to the above-cited patents, sewing machines of this type comprise a clamp frame in which the work is clamped and a so-called

40 stitch frame carrying an upper thread mechanism for manipulating the upper thread, and which is usually in the form of a straight eye-pointed needle, and an under thread mechanism (or, as it is sometimes called, a complementary stitch-forming mechanism) for manipulating the under thread, said under thread mechanism including a curved eye-pointed needle carrying the under thread and which coöperates with the 45 upper needle to concatenate the edge stitches of the buttonhole. In these machines also the stitch frame and the clamp frame are mounted for movement relative to each other, and means are provided whereby

when the machine is started said stitch frame and clamp frame first have a relative movement by which the work clamped in the clamp frame is brought into proper position to have the buttonhole stitched by the upper and under thread mechanisms, and then have 50 such a relative movement as to cause the stitch-forming mechanism to stitch around the edge of the buttonhole, after which said two frames have another relative movement to return the parts to their initial position 55 with the stitched buttonhole removed from the stitch-forming mechanism. During the stitching of the buttonhole, the upper and under thread mechanisms have a turning movement, to enable the edge stitches to be 60 formed around the ends of the buttonhole.

I have provided herein a novel thread-cutting device which is rendered operative by the relative movement of the stitch frame and the clamp frame after the buttonhole 70 has been completely stitched to sever not only the under thread but also the loop of needle thread which is formed by the usual looper as the needle rises from the work. This thread-severing mechanism is secured 75 to the clamp frame and operates beneath the work. The device herein shown is also provided with a thread-clamping device which is automatically rendered operative 80 at the completion of the buttonhole for 85 clamping the under thread and holding the severed end of under thread until the stitching on the next buttonhole is begun so that the stitching operation may proceed without the necessity of the operator taking hold 90 of the severed end of the under thread and holding it while the first few stitches are being formed.

In order to give an understanding of the invention I have illustrated herein a selected 95 embodiment thereof which will now be described after which the novel features of the invention will be pointed out in the appended claims.

In the drawings, Figure 1 is a fragmentary sectional view showing a portion of a buttonhole sewing machine of the type shown in said Patents No. 494,280, No. 498,216, and No. 655,637, said view showing the under thread mechanism in front elevation; Fig. 2 is a top plan view of a portion of the clamp frame carrying the work clamp in a sewing machine of the above type and

showing my improved thread cutter; Fig. 3 is an underside view of the clamping plates shown in Fig. 2; Fig. 4 is a side view of a portion of the under thread mechanism 5 showing a controlling device for the stop cord; Fig. 5 is a plan view partly in section of the stay cord grip; Fig. 6 is a side view of the throat-plate of the under thread mechanism having a thread clamp applied thereto; Fig. 7 is a top plan view of Fig. 6; Fig. 8 is a section on the line $x-x$, Fig. 6; Fig. 9 is a section on the line $y-y$, Fig. 2.

I have not deemed it necessary to illustrate herein a complete sewing machine of 15 the type illustrated in said above-mentioned patents, but have shown in the drawings only such portions of the machine as my improvements apply to.

In the illustrated embodiment of the 20 invention my improved thread cutter is mounted on and associated with the clamp plates by which the work is clamped, and as the general construction and operation of a sewing machine of this type are well known 25 to those skilled in the art, I have confined the illustration in the drawing to such portions of the sewing machine as my invention particularly applies to.

A portion of the clamp frame is shown at 30 1 and it sustains the usual clamp plates 2 and 3 which are removably mounted on the clamp frame and which carry the work clamps 4 and 5 by which the work is clamped in position. This clamp frame is 35 also provided with an opening 6 through which the stitching mechanism operates to apply the edge stitches to the buttonhole.

The stitch frame which carries the upper and under thread mechanism is only partially 40 shown in the drawings and may have the construction illustrated in the above-mentioned patents and which comprises an overhanging arm in which operates the upper needle 7 and the portion 8 situated beneath the clamp 45 frame and in which the under thread mechanism is rotatably mounted. In the type of sewing machine herein illustrated this under thread mechanism comprises a block 9 rotatably mounted in the portion 8 of the 50 frame and carrying at its upper end a throat-plate 12 provided with an opening 11, a curved needle 10 movably mounted on the block and operating through the opening 11 and which co-operates with the upper 55 needle 7 to concatenate the edge stitches of the buttonhole, and other necessary operating parts to effect the buttonhole stitching operation, but which it is not necessary to describe herein in detail.

60 While the operation of buttonhole sewing machines of the type herein illustrated is familiar to those skilled in the art, yet in order to give a proper understanding of my present invention, I would state that when 65 the sewing machine is at rest ready to re-

ceive the work, the stitch frame and clamp frame have such a relative position that the throat-plate 12 of the under thread mechanism is situated in front of the opening 6 of the clamp plate, as shown in Fig. 2. 70 When the work is inserted in the clamp frame and the sewing machine is started the stitch frame and clamp frame move relative to each other first in a direction to bring the throat-plate beneath the aperture 6 75 thereby bringing the upper and lower needles into position to operate through said opening, and then to have a relative movement longitudinally of the buttonhole and of the opening 6, the edge stitches of the 80 buttonhole being formed during such movement and the upper and under thread mechanism having a turning movement in the stitch frame at the proper time to effect the stitching around the ends of the buttonhole, 85 and when the buttonhole stitching is completed and the stitching mechanism brought to rest said stitch frame and clamp frame have another relative movement to bring the parts back into the position shown in 90 Fig. 2. The present invention embodies a novel means which is rendered operative during this latter relative movement of the stitch frame and clamp frame to cut not only the under thread, but also the loop of 95 needle thread which is formed by the usual looper as the needle rises from the work.

The thread-cutting means herein shown 100 comprises a thread cutter 30 pivoted to the clamp plate 2 at 31 and provided with a cutting edge 32 adapted to co-operate with a cutting block 33 carried by the clamp plate 2. This cutter operates adjacent the clamp plate and beneath the work, and means are 105 provided for rendering it operative to cut both threads at the end of the stitching operation. I propose to provide means rendered operative by the above-described relative movement of the stitch frame and clamp frame for actuating the cutter 30, 110 and the construction herein shown constitutes a practical device for this purpose. The cutter 30 has an arm 34 extending therefrom provided with a projection 35 which 115 extends through a slot 36 formed in the clamp plate 2, and this projection is connected to a lever 37 by means of a spring 38. The lever 37 which is pivoted to the under side of the clamp plate 2 at 380 has pivotally connected thereto at 39 a bar 40 that is 120 adapted to be engaged and actuated by a finger 42 extending from the portion 8 of the stitch frame as the stitch frame and clamp frame move relative to each other. The bar 40 is shown as having a laterally-extending arm 44 to which is connected one end of a spring 41, the other end of the spring being secured to a clamp plate 2, said spring acting normally to hold the parts in their inoperative position. The bar 40 is 125

also provided with a plate 46 having at one end a head 47 which is engaged by the finger 42. When the buttonhole has been completed and the stitch frame and clamp frame begin their relative movement into the position shown in Fig. 2 the bar 40 will occupy the dotted line position Fig. 3, and during such relative movement the finger 42 comes into engagement with the head 47, thus moving the bar 40 to the left, Fig. 3, and through the spring 38 operating the cutter 30 to carry the cutting edge 32 thereof against the cutting block 33. The connection 38 constitutes a yielding connection between the cutter and its actuating means, so that when the cutting edge 32 comes against the block, the spring 38 will yield during the final movement of the bar 40, thus preventing any injury to the parts.

20 The construction I have herein shown is such that after the thread has been cut and before the termination of the relative movements of the stitch frame and clamp frame the finger 42 is carried out of engagement with the head 47, thus allowing the spring 41 to throw the cutter into its inoperative position, which position it assumes when the parts come to rest. As herein shown, the bar 40 is provided with a cam surface 49 which 25 is adapted to engage a projection 50 formed on the clamp plate as the bar is moved by the finger 42, the engagement of the cam 49 with the projection 50 causing the bar 40 to move laterally sufficiently to carry the head 30 47 out of engagement with the finger 42. The head 47 will thus be automatically disengaged from the finger 42 after the thread has been cut and before the parts of the sewing machine come to rest.

40 The device herein shown is also provided with thread-clamping means which are associated with the under thread mechanism and by which the under thread is clamped just prior to the operation of the thread 45 cutter, the severed end of the thread being held clamped until the stitching operation on the next buttonhole is commenced. The advantage of the thread clamp is that it holds the severed end of the under thread 50 automatically and without any attention on the part of the operator so that when the stitching operation is started up the first stitches will be formed correctly. When no thread clamp is provided it is necessary for 55 the operator to seize the severed end of the under thread and hold it during the formation of the first stitches, but the presence of the thread clamp prevents this extra operation on the part of the operator. The thread 60 clamp herein shown is associated with the throat plate 12 and is best illustrated in Figs. 6, 7 and 8. The throat-plate 12 has the usual opening 11 therein through which the needle of the under thread mechanism 65 operates and rotatably mounted on the throat-plate is a clamping member 13 which is provided with a clamping edge 14 that cooperates with a clamping shoulder 15 on the throat-plate to clamp the under thread 16. The throat-plate herein shown is provided with the under member 17 and upper member 18 which are connected by a hub 19 in which the opening 11 is formed, and the clamping member 13 is rotatably mounted on the hub 19 between the upper and 70 under members 17 and 18. The upper member 18 is provided with the clamping shoulder 15 above referred to. The clamping shoulder 14 of the clamping member 13 is formed by making the latter with a recess 75 20, one side of which constitutes a clamping edge 14. The clamping member 13 is normally yieldingly held in the position shown in Fig. 7 with the recess 20 covered by the upper plate 18 and with the edge 22 thereof closing one side of the opening 11. For thus yieldingly holding the clamping plate in this position I have provided a spring 21, one end of which is fastened to a projection 90 23 extending from the clamping plate, and the other end of which is fastened to a shoulder 24 formed on the portion 17 of the throat-plate, and a stop 25 secured to the clamping member 13 and engaging a shoulder 26 formed on the portion 17 of the throat-plate, said spring 21 normally holding the stop against the shoulder and the stop serving to properly position the parts. When the buttonhole has been stitched and the stitching frame and clamping frame are 95 moving relative to each other into the full line position shown in Fig. 2, means are rendered operative to turn the clamping member 13 into the position shown in Fig. 8, thus 100 carrying the recess 20 out from under the edge 15 of the part 18, and when this occurs the under thread will drop into the recess 20. After the thread has entered the recess 20 the clamping member is released and the spring 21 operates to bring the parts 105 into the position shown in Fig. 7, thus clamping the under thread 16 between the shoulders 14 and 15. After the thread is thus clamped it is cut between the throat-plate and the work by the cutter 30 as above 110 described, and the severed end of the thread will thus be retained between the clamping shoulders 14 and 15. The means herein illustrated for operating the clamping member comprises a projection 28 extending 115 from said clamping member and a cooperating shoulder 29 formed on the clamp plate 3, said shoulder being so positioned that when the parts are moving from the dotted line position Fig. 2 to the full line position, the projection 28 will engage the shoulder 29, thus turning the clamping member into the position shown in Fig. 8, continued relative movement of the stitch frame and clamp frame causing the projection 28 to wipe by 120 125 130.

the shoulder 29 to allow the clamping member to return to its normal position under the influence of the spring 21 and thus clamp the under thread between the shoulders 14 and 15. The end of the under thread 16 will remain thus clamped until after the stitching operation is again begun on another buttonhole, so that when the under needle is first projected through the opening 11 in the formation of the first stitch of the other buttonhole, as seen in Fig. 6, the end of the under thread is firmly held while the first loop is formed therein through which the upper needle 7 is inserted. The stitching, therefore, proceeds without the waste of any under thread due to the necessity of drawing out the end of the thread, and without the necessity of the operator holding the severed end of the thread. This 20 clamping member *per se* is not claimed herein but claims therefor will be found in my co-pending application Se. No. 864,187, filed September 29, 1913.

In making buttonholes it is customary to 25 lay a stay cord or filling thread around the edge of the buttonhole over which the buttonhole stitches are formed, and I have herein illustrated a clamping device for this stay cord which permits it to be readily fed forward as needed, but will prevent it from being pulled backwardly. The stay cord is shown at 52 and is arranged to pass upwardly through the stitch block 9 in a manner similar to the under thread 16. 30 This improved clamp is associated with the stitch block 9 and comprises an arm or member 53 which is secured to the stitch block and has its upper end curved, as at 54, and provided with a combined cord guide and 35 clamp comprising two members 55 and 56 pivoted to the upper end of the member 53. The member 55 which is pivoted at 57 is formed with an aperture 58 through which the stay cord passes and with an opening 59 in which the nose 60 of the clamping member 56 operates. The member 55 is actuated on by a spring 61 which tends to hold it in the position shown in Fig. 5. The stay cord is fed through the device in the direction of the arrow *a*, Fig. 5, and as it is fed 40 forward the two gripping members 55 and 56 swing forwardly sufficiently to release the grip on the stay cord and allow it to move freely forwardly. If, however, the stay cord is drawn backwardly, the latter is gripped by the projection 60 and is prevented from backward movement. The part 53 is shown as having two projections 65 which limit the swinging movement of the clamping members 55 and 56. This means for controlling the stay-cord is not claimed herein, but is made the subject of a separate application filed by me on November 6, 1914, Se. No. 870,697.

65 It will be noted that in the embodiment

herein illustrated the under thread clamping mechanism is carried by the rotatable under thread mechanism and that while said clamp is carried by the stitch frame, the cutter is carried by the clamp frame, the cutter and clamp being separate from each other.

While I have illustrated herein a selected embodiment of my invention I do not wish to be limited to the constructional features shown.

I claim:

1. In a sewing machine, the combination with upper thread mechanism and under thread mechanism mounted for bodily rotative movement and having thread-manipulating means, of means to sever the under thread at the completion of a stitching operation, and under-thread-gripping means carried by said under thread mechanism and partaking of the bodily movement thereof and situated to engage said thread between the cutting means and the thread-manipulating means.

2. In a buttonhole sewing machine, the combination with a clamp frame, of a stitch frame having upper thread mechanism and under thread mechanism including a throat-plate mounted for bodily rotative movement, said frames being capable of movement relative to each other, means supported by the throat-plate and rendered operative upon the completion of a buttonhole to grip the under thread, and means to sever said thread.

3. In a buttonhole sewing machine, the combination with a clamp frame, of a stitch frame having upper and under thread mechanism the latter being mounted for turning movement in the stitch frame and said frames being capable of movement relative to each other, means carried by an arm turning with the under thread mechanism and rendered operative upon the completion of the buttonhole to grip the under thread between said under mechanism and the work, and means to sever said thread.

4. In a buttonhole sewing machine, the combination with a clamp frame, of a stitch frame having upper thread mechanism and under rotatable thread mechanism, said frames being capable of movement relative to each other, means associated with and partaking of the rotative movement of the under thread mechanism and rendered operative upon the completion of the buttonhole to grip the under thread between said under thread mechanism and the work, and means to sever said thread between the gripping means and the work.

5. In a buttonhole sewing machine, the combination with a clamp frame, of a stitch frame having upper and under thread mechanism, said frames being capable of movement relative to each other, means carried

by the stitch frame and rendered operative upon the completion of the buttonhole to grip the under thread between said under thread mechanism and the work, and means 5 carried by the clamp frame to sever the under thread.

6. In a buttonhole sewing machine, the combination with a clamp frame, of a stitch frame having upper and under-thread mechanism, 10 said frames being capable of movement relative to each other, means carried by the stitch frame and rendered operative upon the completion of the buttonhole to grip the under thread between said under 15 thread mechanism and the work, and means carried by the clamp frame and rendered operative by the relative movement of the clamp frame and stitch frame to sever the under thread.

15 7. In a sewing machine, the combination with a clamp frame and a stitch frame capable of movement relative to each other, of stitch-forming mechanism sustained by the stitch frame, an under-thread clamping 25 mechanism carried by the stitch frame, a thread cutter carried by the clamp frame for cutting the under thread, and means to actuate said cutter and under-thread clamping mechanism.

30 8. In a sewing machine, the combination with a clamp frame and a stitch frame capable of movement relative to each other, of stitch-forming mechanism sustained by the stitch frame, an under-thread-clamping 35 mechanism carried by the stitch frame, a thread cutter carried by the clamp frame, and means to operate said cutter and thread-clamping mechanism by relative movement of the two frames.

40 9. In a buttonhole sewing machine, the combination with a clamp frame, of two clamp plates carried thereby, a stitch frame having stitch-forming mechanism, said frames being movable relative to each other, 45 a thread cutter pivotally mounted on one of the clamp plates, an actuating finger carried by the stitch frame, and means associated with the cutter and adapted to be engaged by said finger whereby the cutter is 50 operated by relative movement of the two frames.

55 10. In a buttonhole sewing machine, the combination with a stitch frame having stitch-forming mechanism and an actuating finger, of a clamp frame having provision for clamping the work, said stitch frame and clamp frame being capable of movement relative to each other, a thread cutter mounted on the clamp frame, and an actuating member connected to the thread cutter and situated normally in position to be engaged by said finger during the relative movement of the two frames upon completion of the buttonhole.

60 11. In a buttonhole sewing machine, the

combination with a stitch frame having stitch-forming mechanism and an actuating finger, of a clamp frame having provision for clamping the work, said stitch frame and clamp frame being capable of movement relative to each other, a thread cutter mounted on the clamp frame, an actuating member connected to the thread cutter and situated normally in position to be engaged by said finger during the relative movement of the two frames upon completion of the buttonhole, and means to disengage said member from the finger when the thread is severed. 70

75 12. In a buttonhole sewing machine, the combination with a stitch frame having stitch-forming mechanism and an actuating finger, of a clamp frame having provision for clamping the work, said stitch frame and clamp frame being capable of movement relative to each other, a thread cutter mounted on the clamp frame, an actuating member connected to the thread cutter and situated normally in position to be engaged by said finger during the relative movement of the two frames upon the completion of the buttonhole, and means to disengage said member from the finger when the thread is severed. 80

85 13. In a buttonhole sewing machine, the combination with a stitch frame having stitch-forming mechanism and a clamp frame having provision for clamping the work, said frames being capable of movement relative to each other, of a thread cutter on the clamp frame, an actuating member movably mounted on the clamp frame and yieldingly connected to said cutter, and means associated with the stitch frame for engaging said actuating member and operating the cutter during the relative movement of said frames. 90

95 14. In a sewing machine, the combination with a clamp frame having provision for clamping the work, of an oscillatory thread cutter movably mounted thereon, a cutting block co-operating with the cutter, an actuating member pivotally connected to the clamp frame, a spring connection between said actuating member and cutter for transmitting power from the former to the latter, means for operating the actuating member, and a spring for returning the cutter to its initial 100 position. 110

105 15. In a sewing machine, the combination with a clamp frame having provision for clamping the work, of a cutting block, an oscillatory thread cutter pivotally mounted on the clamp frame and adapted to be moved toward and from the cutting block, an actuating member also pivotally connected to the clamp frame, a spring connection between said member and the cutter through 115 120

125 130

- which power is transmitted from said member to the cutter, means to give said actuating member a quick forward movement thereby to cause the cutter to have a correspondingly quick cutting movement, and a spring to return said cutter and actuating member to normal position.
16. In a sewing machine, the combination with a stitch-forming mechanism including upper and under thread mechanism, of a clamp frame, two clamp plates sustained thereby, a cutting block secured to one clamp plate, an under thread cutter pivoted to said clamp plate and adapted to coöperate with said block to cut the under thread, an actuating device for said cutter, and a yielding connection between said actuating device and the cutter.
17. In a sewing machine, the combination with a clamp frame having provision for clamping the work, of a stitch frame having stitch-forming mechanism, said frames being capable of movement relative to each other, an oscillatory thread cutter mounted on the clamp frame, an actuating member pivoted to the clamp frame, a spring connection between said member and cutter, and means operative during the relative movement of said frames to move the actuator thereby giving the cutter its operative movement and then to release the actuator.
18. In a sewing machine, the combination with a frame having upper thread mechanism and under thread mechanism including a throat plate, said under thread mechanism being mounted for bodily rotative movement, of means supported by the throat-plate and rendered operative upon the completion of a predetermined stitching operation to grip the under thread, and means to sever said thread.
19. In a buttonhole sewing machine, the combination with a frame having upper thread mechanism and under thread mechanism, the latter being mounted for turning movement in the frame, of means carried by and turning with the under thread mechanism and rendered operative upon the completion of a buttonhole to grip the under thread between said under thread mechanism and the work, and means to sever said thread.
20. In a buttonhole sewing machine, the combination with a frame having upper thread mechanism and under rotatable thread mechanism, of means carried by and partaking of the rotatable movement of said under thread mechanism and rendered operative upon the completion of a buttonhole to grip said under thread between the under thread mechanism and the work, and means to sever said thread between the gripping means and the work.
21. In a buttonhole sewing machine, the combination with a stitch frame having stitch-forming mechanism, of a clamp frame having provision for clamping the work, said stitch frame and clamp frame being capable of movement relative to each other, a thread cutter mounted on the clamp frame, an actuating member connected to the thread cutter, and means carried by the stitch frame and adapted during the relative movement of the frames to move the actuating member to cause it to give the cutter its operative movement and then to release said actuating member thereby to permit the cutter to assume its inoperative position.
22. In a buttonhole sewing machine, the combination with upper and under thread mechanism which are mounted for turning movement to effect the stitching around the end of a buttonhole, of under-thread-gripping mechanism mounted to turn with the under thread mechanism, means to sever the under thread upon completion of a buttonhole, and means to operate the thread-gripping device first to grip the under thread just prior to the severing thereof and then to release said thread after commencement of the stitching operations on the next buttonhole.
23. In a buttonhole sewing machine, the combination with work-holding means, of an under thread mechanism capable of turning about an axis perpendicular to the work and provided with a throat-plate having a thread-clamping edge, of a clamping member rotatable on said throat-plate and provided with a coöperating clamping edge, means to actuate said clamping member to clamp the under thread between said edges upon the completion of a buttonhole, and means to sever the thread between the point where it is clamped and the work.
24. In a buttonhole sewing machine, the combination with work-holding means, of an under thread mechanism capable of turning about an axis perpendicular to the work and having a throat-plate provided with a gripping edge, of a thread-gripping member associated with said throat-plate and having a coöperating thread-gripping edge, means to operate said gripping member to grip the under thread upon completion of the buttonhole, and means to sever the thread between the point where it is clamped and the work.
- In testimony whereof, I have signed my name to this specification, in the presence of two subscribing witnesses.

FRANK ZALESKI.
